UNITED STATES PATENT OFFICE

137,292

DESIGN FOR AN AIRPLANE PROPELLER

Joseph Chojmik, Whiting, Ind.

Application December 15, 1942, Serial No. 109,045

Term of patent 14 years

To all whom it may concern:

Be it known that I, Joseph Chojmik, a citizen of the United States, residing at Whiting, in the county of Lake and State of Indiana, have invented a new, original, and ornamental Design for an Airplane Propeller, of which the following is a specification, reference being had to the accompanying drawings, forming a part thereof.

Figure 1 is a front elevational view of an airplane propeller showing my new design;

Figure 2 is a rear elevational view; and

Figure 3 is a side elevational view thereof.

I claim:

The ornamental design for an airplane propeller, as shown.

JOSEPH CHOJMIK.
